FIG. 10.

UNITED STATES PATENT OFFICE

JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

LOUD-SPEAKING TELEPHONE SYSTEM.

1,084,070.

Specification of Letters Patent.

Patented Jan. 13, 1914.

Application filed November 28, 1910. Serial No. 594,418.

To all whom it may concern:

Be it known that I, JOHN J. COMER, a citizen of the United States of America, and resident of Chicago, Cook county, Illinois, have invented a certain new and useful Improvement in Loud-Speaking Telephone Systems, of which the following is a specification.

My invention relates to telephone systems in general, but more particularly to systems for loud speaking purposes, or similar systems, and especially to systems in which clearness of enunciation and purity of tone are essential.

The object of my invention, generally stated, is to provide an improved and highly efficient loud speaking system, of such character that it may be used for enunciating at a distance, or for musical purposes, either vocal or instrumental, and may be employed in various other ways for which the ordinary system is not adapted.

A special object is to provide a system in which the instruments are adapted to operate satisfactorily with heavy currents, as is desirable, when used for loud speaking purposes.

Another object is to provide a system in which provision is made for accurate adjustment of the different instrumentalities to insure the best results.

Another object is to insure clear enunciation and pure tone in the use of a system of this kind.

It is also an object to provide certain details and combinations tending to increase the general efficiency and render a system of this kind entirely practical for loud speaking and other similar purposes.

To the foregoing and other useful ends, my invention consists in matters hereinafter set forth and claimed.

In the accompanying drawings Figure 1 shows a differential transmitter connected with a loud speaking receiver, together with a source of current and connections therefor in a system embodying the principles of my invention. Fig. 2 is a view similar to Fig. 1, illustrating the manner in which resistance can be employed in place of capacity to obtain the desired result. Fig. 3 is a view similar to Fig. 1, but showing a different arrangement of the resistance through which current is supplied from the battery to the

transmitter. Figs. 4, 5, 6, 7, 8 and 9 are sectional views showing different forms of differential microphone transmitters. Fig. 10 is an enlarged longitudinal section of the operative portion of the loud speaking receiver employed in my said loud speaking system. Fig. 11 is a similar view of the differential microphone repeater employed in said system.

As shown in Fig. 1, the differential microphone A has the front and back electrodes a and a' and the intermediate electrode a^2 . The loud speaking receiver B has an operating coil b , one terminal of which is connected to the electrode a^2 , and the other terminal of which is connected between the condensers C and D, which are connected in bridge of the circuit from the battery E to the front and back electrodes of the microphone. In other words, one pole of the battery is connected with the electrode a , and the other pole is connected to the electrode a' , the lamps e and e' serving as resistance at each side of said battery. With this arrangement the receiver B responds to the differential action of the microphone, by reason of the alternate discharge of the condensers C and D, due to the alternate rise and fall of the resistance at opposite sides of the electrode a^2 , in the manner common to differential transmitters.

In Fig. 2, the arrangement is substantially the same as that shown in Fig. 1, except that in this case lamps, or other resistance devices, I and I' are substituted for the condensers C and D, in the manner shown. Also, in this case resistance I ^{2} is connected in the circuit from one pole of the battery to the front electrode a , and a lesser resistance I ^{3} is connected in the circuit between the other pole of the battery and the electrode a' . In this way the differential action of the transmitter is employed to operate the receiver.

In Fig. 3, the arrangement is exactly like that shown in Fig. 1, with the exception that in this case resistance J is included in the circuit between one pole of the battery and the electrode a , and resistance J' is included in the circuit between the other pole of the battery and the electrode a' . Also, in this case a resistance J ^{2} is connected in bridge of the battery circuit, and in multiple with the condensers C and D. This arrangement,

I find, will give satisfactory results, and will enable the differential action of the transmitter to efficiently operate the receiver.

It is obvious, therefore, that many different ways may be employed for connecting the differential transmitter with a loud speaking receiver, or with a repeater, and that for this reason I do not limit myself to any particular circuit arrangement.

The differential transmitter employed in my improved loud speaking system may be of any suitable, known or approved character. It is preferably, however, of some such form as that shown in Figs. 4 to 9, inclusive, and which are as follows: In Fig. 4, the diaphragm a^3 carries the box a^4 , which latter contains the granular carbon a^5 of the differential microphone. The front and back electrodes a and a' are vibratory with the said box, and the middle electrode a^2 , which separates the chamber of the box into two compartments, is also vibratory with said diaphragm and said box. The stationary electrodes a^6 and a^7 are carried on a stem a^8 , which latter is adjustably connected to the bridge a^9 , which latter is insulated from the balance of the structure. The said front and back electrodes are applied with mica insulations, and the box is also lined with mica insulations, whereby the transmitter may carry heavy currents and become quite hot without injury thereto. It will be observed that the granular carbon is the only medium of connection to or from the electrodes a^6 and a' —that is to say, these two electrodes are electrically connected on the stem by which they are mounted, and current can only pass to or from these electrodes by first passing through the granular carbon. In Fig. 5, the stationary box a^{10} is mounted on the plate a^{11} and contains the front and back electrodes a and a' , the granular carbon a^5 , and the intermediate electrode a^2 , as previously described. The electrode a^2 is connected with the diaphragm a^3 , and the circuit arrangement is the same as that shown, for example, in Fig. 1. In this case the microphone box is also provided with sufficient mica insulation to insure the desired results. In Fig. 6, the construction and mode of operation are substantially the same as shown in Fig. 5, except that in this case the middle electrode a^2 is operated by the yoke a^{12} secured to the diaphragm, and which yoke passes through the sides of the microphone box. Otherwise, the construction is substantially the same and the circuit arrangement is substantially the same as that shown in Fig. 1. In Fig. 7, the construction involves the movable front and back electrodes a and a' and the stationary middle electrode a^2 , which latter is connected by a stem a^{13} with the bridge a^{14} which is insulated from the balance of the structure. The construction here, it will be seen, is substantially the

same as that shown in Fig. 4, except that the front of the microphone box is omitted. The circuit arrangement may be the same as that shown in Fig. 1, or of any other suitable character. Fig. 8 shows a construction and mode of operation substantially the same as that shown in Fig. 7, with the exception that in this case the microphone is composed of a box a^{15} , the end wall of which is secured to the diaphragm a^3 , and operated at its other end with a cap or closure a^{16} . In Fig. 7, as will be seen, the mouth of the box a^{17} is applied to the back of the diaphragm and secured thereto. In Fig. 9, the construction and mode of operation is substantially the same as that shown in Fig. 4, the only difference here being the same as the difference just described between Figs. 8 and 7. In other words, in Fig. 4 the microphone box is composed of two shells a^{18} and a^{19} which have their open ends secured to opposite sides of the diaphragm. In Fig. 9, however, the microphone is made up of two sheet metal boxes a^{20} and a^{21} which have their backs or end walls secured to opposite sides of the end wall, and which have their open ends secured by caps or closures a^{22} and a^{23} . The circuit arrangement for Fig. 9 is the same as that of Fig. 4.

The receiver B, as shown in Fig. 10, comprises a permanent magnet b' , the shorter leg of which is provided with a core or soft iron pole piece b^2 , upon which is mounted the coil b . The longer leg of the permanent magnet is provided with a shoulder b^3 upon which rests the armature b^4 that vibrates in front of the electro-magnet in response to the impulse from the differential transmitter or from the differential repeater. The diaphragm b^5 is connected by a stem b^6 to the lower end of the lever b^7 , which latter has its upper end supported in a fulcrum b^8 . The said fulcrum is carried at the lower end of a screw b^9 , which screw is in turn mounted upon a pivoted or tilting arm b^{10} , being adapted to tilt about an axis at the point b^{11} , when the screw b^{12} is adjusted one way or the other. A spring b^{13} surrounds the screw b^{12} and keeps the arm b normally raised. When the screw b^9 is operated, it raises or lowers the fulcrum b^8 , and thereby changes the leverage of the lever b^7 . When the screw b^{12} is operated, it moves the fulcrum toward or away from the diaphragm, so as to regulate or change the air gap between the armature b^4 and the core b^2 to insure the desired results. The lever b^7 is connected with the upper end of the said armature b^4 by a link b^{14} , whereby the vibrations of said armature are connected through the variable leverage connection to the diaphragm of the receiver. The said variable leverage connection serves to amplify the vibrations produced in the receiver in response to the differential action of the

microphone at the other end of the circuit. With the arrangement shown, a very delicate and accurate adjustment of the parts can be obtained.

The repeater is shown in detail in Fig. 11.

It comprises a microphone having front and back electrodes g and g' , a middle or intermediate electrode g^2 , with granular carbon g^3 between, the said front and back electrodes closing the opposite ends of a box formed by a lava ring g^4 . The electrode g^2 is carried on a stem g^5 that extends through the microphone, whereby the electrode g^2 is movable while the others are stationary.

15 The permanent magnet g^6 has its shorter leg provided with a soft iron core or pole piece g^7 , upon which is mounted the coil G . The longer leg of the permanent magnet is provided with a shoulder g^8 upon which

20 rests the armature g^9 that vibrates in front of the soft iron core or pole piece. This armature is connected with a stem g^5 , and the outer end of the latter is provided with means for engaging a lever g^{10} , which latter

25 has its upper end supported in a fulcrum g^{10} . The said fulcrum consists of a hollow screw disposed vertically in the support g^{11} secured to the face of the microphone box.

The lower end of said lever engages a 30 spring g^{12} that is carried on a pivoted block or arm g^{13} , which latter is provided with an adjusting screw g^{14} that extends therethrough and engages the face or outer surface of the microphone box. By adjusting the screw g^{14} the air gap between the armature g^9 and the core or pole piece g^7 can be regulated or changed at will to insure the best results. When the screw or threaded fulcrum g^{10} is raised or lowered, it

35 changes the leverage of the lever g^{10} , and in this way the instrument can be regulated or adjusted in accordance with the strength of the current, the character of the impulses, or in accordance with any other conditions 40 that are not always the same in different cases. Mica insulation is applied to the outside of the box, in the manner shown, to not only insulate the microphone from the magnet structure, but also to prevent the instrument

45 from being damaged by the heat of heavy currents, it being necessary, in a system embodying the principles of my invention, to sometimes use much heavier currents than is ordinarily employed in the use of telephone systems.

50 From the foregoing, it will be seen that I have combined the differential microphone with a loud speaking receiver, and that the differential action is used for loud speaking, 55 or other similar purposes, in an efficient and highly satisfactory manner. It will also be seen that I employ the differential microphone for the purpose of obtaining clear and smooth enunciation and purity of tone, 60 rather than for the purpose of increasing

the power of the transmission. In a loud speaking system it is very essential, I find, that the enunciation be perfectly clear and smooth, and that the tones be pure and good, as a system of this kind is often necessarily employed for the transmission of music, either vocal or instrumental. The differential action of the microphone is amplified in the receiver, with the result that the tones of either voice or musical instrument may be heard for some distance from the said receiver. The variable leverage system of adjustment for the repeaters and receivers, in a system of this kind, is, I find, very efficient and entirely satisfactory, as by such method a very accurate adjustment is insured, and the best results are obtained.

What I claim as my invention is:

1. In a telephone system, a differential microphone comprising a pair of electrodes and a third electrode movable relatively to said first-mentioned electrodes, a battery and a line circuit, a connection from said third electrode to one side of said line, a connection from each of said other electrodes to opposite sides of said battery, and an inductive connection from the opposite side of said line circuit to said battery.

2. In a telephone system, a differential microphone comprising a pair of electrodes and a third electrode movable relatively to said first-mentioned electrodes, a battery and a line circuit, a connection from said third electrode to one side of said line, a connection from each of said other electrodes to opposite sides of said battery, and an inductive connection from the opposite side of said line circuit to both sides of said battery.

3. In a telephone system, a differential microphone, a line circuit, and a source of current, operatively connected to both sides of said line circuit, a plurality of electrodes for said transmitter, a connection from one of said electrodes to one side of said line circuit, and connections from two other of said electrodes to opposite sides of said source of current, and a bridge including resistance across said last two connections.

4. In a telephone system, a differential microphone, a line circuit and a source of current, operatively connected to both sides of said line circuit, a plurality of electrodes for said transmitter, a connection from one of said electrodes to one side of said line circuit, connections from two other of said electrodes to opposite sides of said source of current, and an inductive bridge across said last two connections.

5. In a telephone system, a differential microphone, a line circuit and a source of current, a plurality of electrodes for said transmitter, a connection from one of said electrodes to one side of said line circuit, connections from two other of said electrodes to opposite sides of said source of current,

an inductive bridge across said last two connections, and a connection from a mid-point of said inductive bridge to the opposite side of said line circuit.

5 6. In a telephone system, a line circuit, a differential transmitter, comprising a pair of stationary electrodes and a movable electrode and a connection from said movable electrode to one side of said line circuit, a 10 source of current and connections from said stationary electrodes to opposite sides of said source of current, a bridge across said last two connections, a pair of condensers in said bridge, and a connection from a point 15 between said condensers to the opposite side of said line circuit.

7. In a telephone system, a line circuit, a differential transmitter, comprising a pair of stationary electrodes and a movable electrode, a connection from said movable electrode to one side of said line circuit, a source of current and connections from said stationary electrodes to opposite sides of said source of current, a bridge across said last 20 two connections, a pair of condensers in said bridge, and a connection from a point between the source of current and said inductive 25 bridge.

said condensers to the opposite side of said line circuit, and a bridge including resistance across said connections between said inductive bridge and said stationary electrode. 30

8. In a telephone system, a line circuit, a differential transmitter, comprising a pair of stationary electrodes and a movable electrode, a connection from said movable electrode to one side of said line circuit, a source of current and connections from said stationary electrodes to opposite sides of said source of current, a bridge across said last 35 two connections, a pair of condensers in said bridge, a connection from a point between said condensers to the opposite side of said line circuit, and a resistance connected in series with each of said connections between the source of current and said inductive 40 bridge.

Signed by me at Chicago, Illinois, this 23rd day of November, 1910.

JOHN J. COMER.
